HARRY VISSERING, OF CHICAGO, ILLINOIS, ASSIGNOR TO CHAS. R. LONG, JR., CO., OF LOUISVILLE, KENTUCKY, A CORPORATION OF KENTUCKY.

FLUID-PRESSURE AGITATOR.

1,201,395.

Specification of Letters Patent.

Patented Oct. 17, 1916.

Application filed November 14, 1912. Serial No. 731,344.

To all whom it may concern:

Be it known that I, HARRY VISSERING, a citizen of the United States, and a resident of Chicago, in the State of Illinois, have invented certain new and useful Improvements in Fluid-Pressure Agitators, of which the following is a specification.

My present invention relates in general to mixing devices and more particularly to agitators for mixing the contents of containers used for the supply of mixtures of fluids, or of mixtures including a fluid and a solid, of different specific gravities, and has special reference to the provision of an improved agitator for mixing the contents of paint barrels, such devices being particularly useful in connection with such paints as employ oil, water, or other relatively light liquid as the fluid vehicle and lead, or other relatively heavy pigment, as a coloring medium.

The principal objects of my present invention are to provide improved means whereby the fluid contents of the barrel may be effectively stirred up, and this with a minimum loss of time, a minimum of expense, and without destruction of the barrel; the provision of an improved device for the purpose characterized, which is provided with automatic means for restraining any accidental removal of the contents of the container; to provide a device so characterized which may be applied with facility to practically any known type of barrel, together with such other objects as may hereafter appear.

Much trouble is encountered and loss incurred at this day in connection with the use of paints having relatively heavy pigment and especially paints which are used in large quantities for railroad purposes, such as painting cars, bridges and the like, since the heavy pigment settles by gravity to the bottom of the barrel, and in order to efficiently stir up and thereby effectively incorporate it with the oil or other fluid vehicle of the paint considerable exertion on the part of the user is required. Within my observation it practically invariably occurs in such cases that the paint is not properly stirred before using and that when nearly all of the fluid content of the barrel is removed, a sediment of from three to six inches of pigment, which has been deposited from the paint theretofore used and which is not available owing solely to the removal of its proper vehicle, will be

found in the bottom of the barrel. By reason of the fact that it requires so much exertion on the part of the user to obtain a fresh supply of oil and properly work it up with this pigment, such pigment is usually thrown away, which causes a manifold loss, first, that the pigment is wasted, second, the paint from which it is deposited does not contain either the color or the body which it should have, third, time is unnecessarily spent in endeavoring to incorporate the pigment in the fluid vehicle by hand, to which may be added, fourth, that in order effectively to stir up the contents of the barrel it is necessary to remove one head therefrom, consequently making the barrel unfit for future use and therefore unsalable, all of which objections not only render a given paint less effective than it should be, but also make both the cost thereof and that of applying the same greater than it should be.

In the attainment of the objects above set forth and overcoming the disadvantageous conditions suggested, I have provided the constructions illustrated in the accompanying drawings wherein—

Figures 1, 2 and 3 are sectional, perspective views of portions of barrels having devices embodying my present invention applied thereto; Fig. 4 is an enlarged detail view of a portion of the device shown in Fig. 1.

In the drawings I have indicated a barrel, 10, formed of the usual staves, 11, and having a head, 12, the staves being held in position by hoops, 14—14, in the customary manner. For the purpose of agitating the contents of the barrel and thereby effecting an intimate commingling thereof, and in the case of fluids containing a relatively heavy content which should be held in suspension therein, but which tends to gravitate toward the bottom head, 12, of the barrel and form a sediment there, stirring up the sediment and mixing it with the fluid, I employ a pipe, 15, having perforations, 16, one end of the pipe being preferably covered by a tight cap, 17, and the opposite end being carried by a hollow plug 18, which preferably has threaded engagement with an aperture formed in one of the staves, 11, as indicated at 19. The hollow plug, 18, is preferably threaded interiorly at one end as indicated at 20 for the reception of the pipe, 16, and at the opposite end its periphery is given the

form of a nut as indicated at 21 whereby it may be screwed into position, such end of the plug being interiorly threaded for the reception, first, of the closing plug, 22, and, 5 second, for the attachment thereto of a connection, such as a pipe 23 to a source of compressed air (not shown.) For the purpose of restraining efflux of the fluid contents of the barrel through the hollow plug, 18, after 10 the removal of the closing plug, 22, for the attachment of the pipe, 23, to such plug, 18, I employ a sliding check valve, 24.

The form of device just described is perhaps the most economical in manufacture 15 and the simplest in form, and is the one preferably applied by me to barrels having a sufficient distance between the first and second hoops to permit its application.

Referring now to the device of Figs. 2 20 and 3 it will be here observed that I have illustrated a form of device which I employ for application to barrels which have their hoops so placed that the previously described form of construction may not conveniently be employed. In the present form 25 of device it will be observed that the perforated pipe, 15^a, is bent as indicated at 25 and in lieu of the sliding check valve of the first mentioned device I employ the 30 ball valve, 24^a. The bend at 25 permits insertion of the pipe through and fastening of the plug in the bottom of the barrel, without disturbance of its parallelism to such bottom.

35 In mixing paints containing an extra heavy pigment and other fluids, for the mixing of which the devices of Figs. 1 and 2 would be inadequate, I preferably employ the form of device shown in Fig. 3 in which 40 it will be observed on inspection of Fig. 3 that the pipe 15^b is given the form of a continuous spiral, I being thus enabled to, as it were, screw it into the barrel through a bottom opening. In order to secure the 45 most effective results from the use of compressed air, the perforated pipe 15, should be kept substantially parallel to the bottom of the barrel and should not be placed too far away from the sediment, and it is ap- 50 parent that the use of the spiral form of pipe permits the placing of an increased length thereof in the barrel without removing any material portion thereof from the normal level of the sediment.

55 I have found that in the use of barrels equipped with my improved agitator, when a hole such as is indicated at 26 is bored through the head, 13, of the barrel, it is unnecessary to remove the upper head of 60 the barrel since such hole is adequate to relieve the air pressure by venting it to the

atmosphere. When the barrel is standing in the position indicated in the drawings, the agitator arranged across the bottom, and air admitted to the perforated pipe under 65 pressure, not only is the whole fluid content of the barrel, such as the vehicle and pigment held in suspension therein, thoroughly stirred up and mixed without the least effort on the part of the workmen, but 70 also any sediment which may have been precipitated to the bottom of the barrel is washed up therefrom by the air blast and thoroughly commingled with such fluid content. 75

Having thus described my invention and illustrated its use, what I claim as new and desire to secure by Letters Patent is:

1. In an apparatus of the character described, in combination, a hollow plug provided with means whereby it may be attached to a container, means for connecting the hollow plug to a source of fluid pressure and a stop-plug for preventing gravitation outwardly of fluid through said hollow 85 plug, a check valve adapted to act as an auxiliary means for such prevention on the removal of the stop-plug. 80

2. In combination with a container, an agitator comprising, in combination, a hollow plug exteriorly threaded to engage with said container, a perforated pipe carried at one end by said plug, said pipe being closed at its opposite end and arranged substantially horizontal to and having its major 95 portion spaced away from the head of said container, and a connection through said plug for a source of compressed fluid, external means for closing said connection, and a check valve for restraining back flow 100 of fluid through said connection. 90

3. In combination with a container, an agitator comprising, in combination, a hollow plug exteriorly threaded to engage with said container, a closure for said plug disposed exteriorly of the container, and a perforated pipe having threaded engagement with said plug at one end thereof, the opposite end of said plug being threaded for the reception of the closure and adapted for 110 a connection to a source of fluid pressure, a check valve being arranged in said hollow plug for restraining back flow of fluid therethrough. 105

In testimony whereof I have hereunto 115 signed my name in the presence of the two subscribed witnesses.

HARRY VISSERING.
